WATER SWEEPER FOR FLOORS OR SIMILAR
PLANAR SURFACESCharles E. Goodrich, 4024 N. 94th St.,
Omaha, Nebr. 68134

Filed Nov. 15, 1971, Ser. No. 199,093

Term of patent 14 years

Int. Cl. D23—01

U.S. Cl. D23—34

FIG. 1 is a perspective view of a water sweeper for floors or similar planar surfaces, showing my new design.

FIG. 2 is a right side elevational view of my new design, the left side elevational view being a substantial mirror image thereof;

FIG. 3 is a rearward elevational view thereof; and

FIG. 4 is an enlarged bottom plan view thereof, the handle being broken away for convenience of illustration.

I claim:

The ornamental design for a water sweeper for floors or similar planar surfaces, as shown and described.
